PICTURE FRAME

George A. Romancy, St. Helen, Mich. 48656
Filed Mar. 13, 1972, Ser. No. 234,448

Term of patent 14 years

Int. Cl. D6—07
U.S. Cl. D6—244

FIG. 1 is a front elevational view of a picture frame showing my new design, the rear view being substantially a mirror image thereof;

FIG. 2 is a right side elevational view, the left side being substantially a mirror image thereof;

FIG. 3 is a top plan view thereof;

FIG. 4 is a bottom plan view thereof; and

FIG. 5 is a perspective view thereof.

I claim:

The ornamental design for a picture frame, as shown and described.
